UNITED STATES PATENT OFFICE.

FRANK M. FARGO, OF CHICAGO, ILLINOIS, AND GEORGE L. THOM, OF BROOKLYN, NEW YORK; SAID THOM ASSIGNOR TO SAID FARGO.

ALARM.

1,203,995.

Specification of Letters Patent.

Patented Nov. 7, 1916.

Application filed June 18, 1915. Serial No. 34,939.

To all whom it may concern:

Be it known that we, FRANK M. FARGO, a citizen of the United States, residing at Chicago, in the county of Cook and State 5 of Illinois, and GEORGE L. THOM, a citizen of the United States, residing at Brooklyn, in the county of Kings and State of New York, have invented certain new and useful Improvements in Alarms; and we do 10 hereby declare the following to be a full, clear, and exact description of the invention, such as will enable others skilled in the art to which it appertains to make and use the same.

15 This invention relates to alarms such as burglar alarms or the like, and more particularly to that type wherein a detonation is had when a moving part, such as a door or window is changed from its relative position 20 with respect to a fixed part, such as a door frame.

25 An object of this invention is to provide an alarm which may be easily applied to the moving and stationary parts of a door, window or the like.

A further object of this invention is a provision of an alarm having parts thereof detachably mounted.

30 A further object of this invention is a provision of a detonating alarm having one portion thereof to sound upon restricted movement of the movable and fixed ends, and then a second or more detonation upon continued movement of one of the fixed ends 35 with respect to the other.

A further object of this invention is a provision of fastening means which may be permanently applied to the relative parts of 40 closures such as doors, windows or the like, of which one of the fastening means is attached to the fixed part of the closure and the other fastening means is attached to the moving part of the closure and a detachable alarm carried by said fastening means.

45 Further objects will be apparent from the following specification, appended claims and drawings thereof, in which—

50 Figure 1 indicates a corner of a room, having a door and window in the wall thereof, and Fig. 2 is a perspective view of one form of alarm.

An alarm of this kind is applicable to the sealing of doors, windows or other types of closures against malicious opening and its

application will be appreciated as for locks, 55 hotels, residences and the like, because provision is made by which the alarm may be properly positioned to afford protection when so desired and otherwise, the alarm may be removed from its fastening means 60 so that the same alarm may be used repeatedly until it has served as an alarm at which time, it is only necessary to replace the detonating portion.

Referring to the drawings, there is shown 65 a door frame 10 having the door 11 hinged therein and said door having a knob 12 by which the latch may be manipulated. Attached to the door and door frame are the fastening tabs 13 between which the alarm 70 is suspended and this alarm comprises tabs 14 which are engageable with the tabs 13 and between the tabs 14 and connected thereto are one or more detonating alarms 15. These alarms 15 are of that type commonly 75 used as favors for parties in which tension applied to the opposite ends of tapes establishes frictional engagement between the fastened ends of said tape and thereby creates the explosion. When it is applied, as 80 shown in the drawings herewith, for obvious reasons it may be desired to provide the alarm as shown in Fig. 2 of the drawings, in which the tabs 14 are connected by two alarms of different lengths so that as 85 tension is applied by moving the tabs 13 apart, one alarm is sounded and continued movement sounds the second alarm so that should one alarm fail to awaken a sleeper, 90 the second one will accomplish its purpose 90 as is readily understood. For use in a residence, by adding another alarm or as many as desired, it is possible to distinguish between the sealing alarms at the front or rear of the house by the number of detonations.

The same device may be applied to the window as shown, in having one of the tabs 13 attached to the sash and the other attached to the frame as shown, so that as 100 the sash is raised, tension is applied to the tapes 16 to sound the alarm 15. It may be desired to use invisible connections between the tabs 14 and alarms 15 and this feature is shown in Fig. 2 of the drawing in which 105 the connection comprises threads 16. Tabs 13 may be of any desired material and will preferably have the opposite faces thereof

gummed at points indicated on the drawing so that each tab may be used more than once if so desired.

Having thus described this invention, we 5 claim:—

1. In an alarm of the class described, fastening means for attachment to the relatively moving parts of a closure, a removable alarm detachably connected to said fastening means, said alarm comprising a plurality of units of different lengths to explode successively when continued tension is exerted by the fastening means of said alarm.
- 15 2. In an alarm of the class described, fastening tabs for attachment to the relatively moving parts of a closure, said tabs having the opposite faces thereof gummed, said tabs extending beyond the gummed portions thereof, each of said extensions having an opening therein, detonating alarms detachably carried by said tabs, said alarms having heads for engagement in the openings

formed in said extensions and said alarms comprising a plurality of independent sections carried by said heads, said sections being of different lengths to successively sound the alarms as the heads are moved farther apart.

25 3. In an alarm of the class described, tabs for attachment to the separable parts of a closure, alarms carried by said tabs, said alarms comprising sections of different lengths to be successively broken as said tabs are moved apart.

30 35 In testimony whereof we affix our signatures in presence of two witnesses.

FRANK M. FARGO.
GEORGE L. THOM.
